(57) **CLAIM**

The ornamental design for a snowmobile hood, as shown and described.

DESCRIPTION

FIG. 1 is a front left perspective view showing a snowmobile hood according to our design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front left perspective view of a typical snowmobile (shown in broken lines) including the hood according to our design.

Throughout the Figures, broken lines showing structure and environment are for illustrative purposes only and form no part of the claimed design.

1 Claim, 6 Drawing Sheets
